UNITED STATES PATENT OFFICE.

BENJAMIN LESHOWITZ, OF BROOKLYN, NEW YORK, ASSIGNOR TO COLONIAL METAL SPINNING & STAMPING CO., OF NEW YORK, N. Y.

DESIGN FOR A BACKPLATE FOR LIGHTING FIXTURES.

Application filed March 23, 1926. Serial No. 17,025. Term of patent 3½ years.

To all whom it may concern:

Be it known that I, BENJAMIN LESHOWITZ, a citizen of the United States, residing in the city of New York, borough of Brooklyn, in the county of Kings and State of New York, have invented a new, original, and ornamental Design for a Backplate for Lighting Fixtures, of which the following is a specification, reference being had to the accompanying drawings, forming a part hereof, in which—

Figure 1 is a plan view of a backplate showing my new design; and

Figure 2 is a side view of the backplate shown in Figure 1.

I claim:

The ornamental design for a backplate for lighting fixtures, as shown.

BENJAMIN LESHOWITZ.
